UNITED STATES PATENT OFFICE.

GEORGE W. FREEMAN, OF WEST HOBOKEN, NEW JERSEY, ASSIGNOR OF ONE-HALF TO FRANK HALL, OF RIDGEFIELD, NEW JERSEY.

HEMSTITCHING ATTACHMENT FOR SEWING-MACHINES.

SPECIFICATION forming part of Letters Patent No. 777,621, dated December 13, 1904.

Application filed January 15, 1904. Serial No. 189,181. (No model.)

To all whom it may concern:

Be it known that I, GEORGE W. FREEMAN, a citizen of the United States, residing at West Hoboken, in the county of Hudson and State 5 of New Jersey, have invented new and useful Improvements in Hemstitching Attachments for Sewing-Machines, of which the following is a specification.

This invention relates to hemstitching attachments to sewing-machines.

The object of the invention is to provide an attachment of the class described which shall be adapted for use in connection with any form of presser-bar, which may be used as a plain-stitch attachment without altering the tensions, which will without the necessity of close attention effect in a rapid and simple manner the formation of hemstitches, and which shall be simple of construction, efficient 20 and durable in use, and easy of manufacture.

With the above and other objects in view, as will appear as the nature of the invention is better understood, the same consists in the novel construction of a hemstitching attachment for sewing-machines, as will be herein- 25 after fully described and claimed.

Generally stated, the device of this invention contemplates in its construction an arm for attachment to the presser-bar of the machine and a plate, preferably integral with the arm and of a length greater than that of the feed-bar, whereby a portion of the attachment is caused to coact with the feed-bar to effect proper feeding of the material through the machine, and the other portion is adapted to coact with the bed-plate to hold the fabrics taut when the feed-bar is not operating. In addition to these portions of the attachment or plate there is provided intermediate of its 30 ends a portion constituting a fabric-separator, the same being of less thickness than the remaining portions of the plate, so that in operation the feed-bar does not contact with it, thereby positively preventing the under fabric from traveling faster than the upper fabric. By this arrangement bunching of the assembled fabrics is obviated, causing the assembled fabrics to be combined in a neat and positively effective manner. The upper sur-

face of the plate is inclined from the left to- 50 ward right—that is to say, it declines toward the right—and this incline tends to draw the upper fabric into the fabric-guides formed in the plate and spaced by the separator above described. The separator is further provided 55 with a needle-hole, communicating with which is an escape-slot, the manner in which the attachment operates being such that when the needle is ascending or descending the fabrics will be prevented from being drawn into the 60 needle-hole, and thus cause uneven sewing or puckering of the goods. This result is secured by the terminal portions of the plate, which coact with the bed-plate to clamp the 65 goods firmly thereagainst.

The attachment is constructed in such a manner as to permit of its being readily assembled with any ordinary sewing-machine without requiring any changes in the structural arrangement of the latter—that is to 70 say, it will be made to fit the various makes of sewing-machines—and in use takes the place of the presser-foot without necessitating any change of the thread tensions, and by reason of the simplicity of construction, all 75 the parts being by preference integral, danger of derangement in use is practically obviated.

In the accompanying drawings, forming a 80 part of this specification, and in which like characters of reference indicate corresponding parts, there is illustrated one form of embodiment of the invention capable of carrying the same into practical operation, it being understood that the elements therein exhibited may be varied as to shape, proportion, and exact manner of assemblage without departing from the spirit thereof.

In the drawings, Figure 1 is a perspective view of the attachment. Fig. 2 is a view in 90 side elevation, showing the attachment secured to the presser-bar of the machine and in co-operative relation with the bed-plate thereof, the feed-bar being shown partly broken away. Fig. 3 is a view in front elevation of the attachment.

Referring to the drawings, A designates the presser-bar of an ordinary sewing-ma-

chine, B the bed-plate, and C the feed-bar. As these parts may be of the usual or any preferred construction, detailed description thereof is deemed unnecessary.

The fabrics being assembled are designated by D and E, the fabric designated by D being the upper fabric and that designated by E being the lower fabric.

The attachment of the present invention 10 comprises a shank or arm 1, adapted for attachment to the presser-bar, and a plate 2, the plate, as shown in Fig. 3, being inclined on its upper side downward toward the right, said incline subserving the function presently 15 to be described. The plate 2, as clearly shown in Fig. 2, is of greater length than the feed-bar, and that portion 3 disposed over the feed-bar is the only part which is adapted to 20 coact directly therewith, the terminal portion 4 of the plate being disposed out of the path of travel of the feed-bar and being designed to coact with the bed-plate to clamp the fabrics D and E firmly therebetween when the needle ascends or descends, thereby to prevent the 25 fabric being drawn through the needle-hole 5 of the plate. This needle-hole is formed in a tongue 6, which is separated from the portions 3 and 4 of the plate by recesses 7 and 8, in which the upper fabric is disposed, the fabric being 30 brought upward through the space 8, over the tongue 6, and thence downward through the space 7. As clearly shown in Fig. 1, one wall, 9, of the tongue 6, which constitutes a fabric 35 separator, is beveled, as is also one wall, 10, of the recess 7, and by this arrangement the frictional resistance to the passage of the goods through the attachment is reduced to a minimum. In order to permit the thread to 40 escape from the tongue 6, there is an escape-slot 11 provided, which communicates with the needle-hole 5, and to cause the upper fabric D to remain within the attachment and to 45 check it against any tendency to work out of the slot the upper wall or face of the plate is inclined, as shown in Fig. 3. Under the arrangement shown when the feed-bar is depressed the fabrics are held firmly between the portions 3 and 4 of the attachment and the bed-plate B while the needle is making 50 the stitch. As the needle is withdrawn the feed-bar rises and lifts the attachment from the bed-plate and acts upon the fabrics under a part of portion 3 and carries them rearward. The feed-bar then descends, allowing 55 the portions 3 and 4 of the attachment to clamp the fabrics to the bed-plate while the next stitch is being made.

By reducing the under face of the fabric-separator 6 so that it lies above the plane of 60 the portions 3 and 4 there will be no contact between the separator and the feed-bar, so that the latter cannot effect feeding of the fabric through the machine. In fact, as shown, the only feed takes place under the portion 3

of the plate, the guide portions 3 and 4 operating positively as a fabric-clamp. 65

In order to understand the manner in which the attachment works, an explanation is furnished of a complete cycle of a sewing-machine provided therewith. Let it be supposed 70 that the needle is up and that the presser-bar to which the attachment is secured held up from the bed-plate by any one of the devices forming a part of every sewing-machine to permit insertion of the fabric. When the 75 needle is up, the feed-bar is always raised above the bed-plate. The presser-bar is now released in the usual manner, which brings the portion 3 of the attachment into contact with the feed-bar with the fabrics interposed. 80 The machine is now started and the feed-bar continues its rearward movement, which was but about half completed at the start. Having completed this movement, the feed-bar descends below the bed-plate, allowing the attachment to come into contact with the bed-plate at the portions 3 and 4 with the fabrics between, thus holding the fabrics firmly 85 on each side of the needle, which now descends and makes the stitch. In the meantime 90 the feed-bar has been moved forward below the level of the bed-plate, and as the needle rises the feed-bar also rises, coming into contact with the fabrics under the portion 3 of the attachment. This upward movement of the feed-bar also raises the attachment from contact with the bed-plate and releases the fabrics under the portion 4 of the attachment, but grips them firmly between the portion 3 of the attachment and the feed-bar. 95 The feed-bar now starts on its rearward movement and carries the fabrics with it and presents them for the next stitch. This last movement brings the parts back to the point 100 in the operation of the machine from which 105 they started.

It will be seen from the foregoing description that the attachment of this invention, while being exceedingly simple in construction, will be found thoroughly efficient and durable in use and will in a positive and certain manner eliminate certain objectionable features hereinbefore present in devices of this character. 110

Having thus described the invention, what 115 I claim is—

1. An attachment of the class described, comprising a shank or arm, and a plate disposed at right angles thereto and provided near one end with a portion to engage the feed-bar and bed-plate of a sewing-machine, and its other end with a portion to coact with the bed-plate of the machine to clamp the goods against movement, the two parts being spaced by a fabric-separator of less vertical thickness than the plate and having therein a needle-hole and an escape-slot. 120 125

2. An attachment of the class described in-

cluding a plate, having means for attaching the same to the presser-bar of a sewing-machine, and having two recesses which divide the plate into three fabric-guides, the intermediate guide being a fabric-separator, the front walls of the intermediate and rear guides respectively being inclined and converging toward the upper surface of said plate, the under surfaces of the outer guides being in a common horizontal plane to simultaneously clamp the fabric upon the bed-plate and beneath the

under surface of the intermediate fabric-separator, said fabric-separator having a needle-hole and an escape-slot.

In testimony whereof I have hereunto set my hand in presence of two subscribing witnesses.

GEORGE W. FREEMAN.
